UNITED STATES PATENT OFFICE

GEORGE L. DANFORTH, JR., OF CHICAGO, ILLINOIS, ASSIGNOR, BY MESNE ASSIGNMENTS, TO OPEN HEARTH COMBUSTION COMPANY, OF CHICAGO, ILLINOIS, A CORPORATION OF DELAWARE

OPEN-HEARTH-FURNACE CONSTRUCTION

Application filed November 28, 1921. Serial No. 518,258.

This invention relates to a new and improved open hearth furnace construction and more particularly to the design and construction of ports for such furnaces.

5 As is well known in the art, open hearth and similar metallurgical furnaces are double ended and are periodically reversed in their operation. Each end of the furnace thus serves alternately to introduce the air 10 and fuel and to carry off the products of combustion. The products of combustion are much higher in temperature than the incoming air and fuel and greatly exceed the air and fuel in volume. It is, therefore, necessary to so proportion ports and passages 15 of the furnace as to adequately carry off the large volume of the products of combustion. Obviously, when so proportioned, the ports and passages exceed in size the area necessary to properly introduce the air and fuel. This excess size of the ports and passages 20 renders it difficult to adequately control the mixture of the air and fuel and thus to control the length and direction of the flame.

25 A further difficulty with such furnaces lies in the fact that the outgoing products of combustion are of such a temperature as to wear away those portions of the furnace walls which define the ports. This wearing away tends to make more difficult the control of the air and gas.

It is an object of the present invention to provide port defining means in an open hearth or similar furnace which means are 35 movable into and out of operative position.

It is a further object to provide such means which will adequately direct the incoming air and fuel when in the operative position and which will leave the passages 40 clear for carrying off the products of combustion when in the inoperative position.

It is also an object to provide port defining means which upon the outgoing end are 45 withdrawn from the path of the heated outgoing gases.

It is an additional object to provide a 50 port construction which may be applied to existing furnaces without material alterations therein.

Other and further objects will appear as the description proceeds.

Broadly, my invention comprises movable means associated with the air and fuel passages of a metallurgical furnace in such a 55 manner as to selectively form restricted ports for such passages or to leave unrestricted the full opening of said passages.

In the particular form which I have chosen for purposes of illustration, this port defining means comprises a hood, movable and slidable through the end of the furnace and adapted when in its inner position to form a forwardly opening port for the fuel uptake and to cooperate with the furnace 60 walls and air uptakes to form air ports straddling the gas port.

I have illustrated this preferred embodiment in the accompanying drawings, in 70

Figure 1 is a fragmentary longitudinal section showing one port end of an open hearth furnace with my invention applied thereto.

Figure 2 is a section taken on line 2-2 75 of Figure 1; and

Figure 3 is a section taken on line 3-3 of Figure 2.

Referring now to the drawings, the furnace has the melting chamber 5, the roof 80 6, the air uptakes 7 and the gas uptake 8. That portion of the furnace between the uptakes and the melting chamber is somewhat restricted by the inwardly projecting piers 9. As best shown in Figure 3, longitudinally 85 extending guideways 10 are provided upon either side of the gas uptake 8. These guideways as shown, are hollow and will preferably be water cooled. Fitting upon these guideways is the hood 11 provided with the water cooled frame 12. This hood is movable through the opening 13 and through the end wall 14 of the furnace to the dotted line position of Figure 1.

When in its inner position, as best shown 95 in Figure 1, the hood forms a gas port of usual contour. This port directs the gas stream into the melting chamber. As best shown in Figures 2 and 3, the hood also cooperates with the furnace roof and the 100

piers 9 to restrict the passage space between the air uptakes 7 and the melting chamber. As shown in Figure 3, these two uptakes join straddling the hood and forming the air port. Air thus enters in a blanketing stream upon the sides and top of the gas stream.

When the hood is removed to its outer position, the three uptakes are entirely unrestricted by the hood and their full area is effective to carry off the products of combustion. The hood in its outer position also is out of path of the heated discharge gases and is not worn away by their action, and the life of the port is thus materially increased.

While I have shown one preferred form of my invention it is obvious that it may be modified in many ways to cooperate with various forms of passages and furnaces. It is my intention to cover all such modifications to meet varying conditions as come within the spirit and scope of the following claims.

I claim:

1. In a reversible metallurgical furnace, laterally spaced air and fuel passages and means slidable longitudinally of the furnace associated with an intermediate passage adapted to form a restricted port for said passage and a deflecting wall adjacent the lateral passages.

2. In a reversible metallurgical furnace, laterally spaced air and fuel passages and movable means associated with an intermediate passage adapted to form a restricted port for said passage, said means being located spaced from the furnace walls as to cooperate with said walls to form restricted ports for the laterally placed passages.

3. In a reversible metallurgical furnace, a fuel uptake, air uptakes located laterally of the fuel uptake, and movable means associated with said uptakes and adapted to form a restricted port for the fuel uptake and deflecting walls adjacent the air uptakes.

4. In a reversible metallurgical furnace, a fuel uptake, air uptakes located adjacent the fuel uptake, and a movable hood associated with the fuel uptake in such manner as to form a forwardly extending port therefor and to form deflecting walls adjacent the air uptakes.

5. In a reversible metallurgical furnace, a fuel uptake, air uptakes located laterally of the fuel uptake, and a hood slidably associated with the fuel uptake in such manner as to form a forwardly extending port therefor and to form deflecting walls adjacent the air uptakes.

6. In a reversible metallurgical furnace, a fuel uptake, air uptakes located laterally of the fuel uptake, and a movable hood associated with the fuel uptake in such manner as to form a forwardly extending port there-

for, said hood being so related to the furnace walls as to cooperate with said walls to form restricted ports for the air uptakes.

7. In a reversible metallurgical furnace, a fuel uptake, air uptakes located laterally of the fuel uptake, and a movable hood associated with the fuel uptake in such manner as to form a forwardly extending port therefor, said hood being so related to the furnace walls as to cooperate with said walls to form restricted ports for the air uptakes which ports straddle the hood forming the gas port.

8. In a reversible metallurgical furnace, a fuel uptake, air uptakes located adjacent the fuel uptake, and means slidable longitudinally through the furnace wall associated with said uptakes and adapted to form restricted ports for the uptakes.

9. In a reversible metallurgical furnace, air and fuel passages and movable means associated with said passages adapted to form a restricted port for the fuel passage, and deflecting walls adjacent the air passage, said means being adapted in one position to leave all said passages unrestricted.

10. In a reversible metallurgical furnace, a fuel uptake, air uptakes located adjacent the fuel uptake, and means slidable longitudinally through the furnace wall associated with said uptakes and adapted to form restricted ports for the uptakes, said means being adapted in its outer position to leave the openings of all said uptakes unrestricted.

11. In a reversible metallurgical furnace, three laterally spaced uptakes, guideways located laterally of the central uptake, and a hood slidable through the end wall of the furnace upon said guideways, the hood forming a forwardly facing port for the central uptake when in its inner position.

12. In a reversible metallurgical furnace, three laterally spaced uptakes, guideways located laterally of the central uptake, and a hood slidable through the end wall of the furnace upon said guideways, the hood forming a forwardly facing port for the central uptake when in its inner position and being of such height as to allow a clearance between the hood and furnace roof whereby ports straddling the central port are formed for the side uptakes.

13. In a furnace of the character described having fluid passages, of a port arranged at each end of the furnace, said ports being adapted to be alternately projected within the furnace and removed therefrom, a supporting structure for each port, said structures being mounted at the ends of the furnace and communicating with said passages, water-cooled means for both the ports and said supporting structures, and said ports being slidably mounted on said supporting structures and controlling the admittance and discharge of said fluids to and from

the furnace through said supporting structures for the purpose specified.

14. An end construction for regenerative open hearth furnaces having a throat opening into the hearth, an uptake flue leading to said throat, and a member movable across the uptake toward or away from said throat to vary as desired the effective area of the port.

10 15. In a reverberatory furnace, a furnace head having air and gas ports and means to move one of the ports with respect to the other to control the relative areas of their mouths.

15 16. In a reverberatory furnace, a furnace head having an air port and a gas port, one of the ports being tapered with respect to the other and one of said ports movable longitudinally of the tapered port to control the 20 discharge area at its mouth.

17. In a reverberatory furnace, a furnace head having air and gas ports and means to vary the relative area of the mouths of said ports, the area of the air port being unequally 25 distributed around said gas port.

18. In a reversible metallurgical furnace, a fuel uptake, an air uptake located adjacent the fuel uptake, and means slidably longitudinally through the furnace wall associated with said uptakes and adapted to form 30 restricted ports for the uptakes.

Signed at Chicago, Illinois, this 23rd day of November, 1921.
